WINDING STEM CONSTRUCTION FOR WATCHES

Albert Schwartz, Philadelphia, Pa.

Application February 8, 1956, Serial No. 564,231

5 Claims. (Cl. 58—68)

The present invention relates to improvements in watches, and more particularly, to an adaptor for the winding stems thereof, and namely an adaptor for converting a standard watch winding stem into a split winding stem.

The recent relatively widespread use of solid back watch-cases has lead to the adoption of the so-called split winding stem which is inserted after the movement is in the case. The split winding stem differs from the standard winding stem in that the latter is provided with an outer threaded end onto which the crown is threaded, while the split winding stem is not provided with a threaded end, but instead is provided with an axially disposed socket having outwardly extending lips. A bulbous head crown type is engaged with the split winding stem, with the crown's head being received within the socket.

The use of differing forms of winding stems has greatly complicated the inventory and storage problems of watch repairmen. Thus, watch repairmen are now required to keep in stock a supply of standard winding stems, and also a supply of split winding stems.

This invention has as an object the provision of an adaptor for enabling a watchmaker to convert a standard winding stem into a split winding stem.

This invention has as another object the provision of a two-piece winding stem which may be used in conjunction with crowns having bulbous heads.

Other objects will appear hereinafter.

For the purpose of illustrating the invention there is shown in the drawings a form which is presently preferred; it being understood, however, that this invention is not limited to the precise arrangements and instrumentalities shown.

Referring to the drawings wherein like reference characters refer to like parts:

Figure 1 is an elevational view of a standard winding stem.

Figure 2 is an elevational view of the adaptor of the present invention.

Figure 3 is an elevational view of the winding stem of the present invention including the adaptor of the present invention mounted upon a standard winding stem which has been cut in order to conform therewith.

Figure 4 is an enlarged fragmentary sectional view of the winding stem of the present invention operatively positioned within a watch-case.

Referring to the drawings and initially to Figure 1 there is shown therein a standard winding stem designated generally by the numeral 10 in the form in which said winding stem is supplied to watchmakers. Stem 10 is provided with an elongated threaded end 21 designed for threaded engagement with a crown of the conventional type having female threads. Adjacent the threaded end 21 is a collar 14, sometimes referred to as the winding stem shoulder. Adjacent collar 14 is a slot 16 comprising a thinner cylindrical portion than collar 14.

2

A second collar 18 which is sometimes referred to as the hub is positioned intermediate slot 16 and winding pinion shoulder 19, and a squared section 20. Squared section 20 is provided for the reception of the clutch and the winding arbor of the watch's movement, and is sometimes referred to as the winding pinion square. A bearing or pilot bearing 22 is provided at the other end of squared section 20.

The adaptor of the present invention designated generally by the numeral 24 comprises a generally cylindrical member axially threadably bored at one end to form female threads or threaded socket 26, the threads having a tap permitting them to be matingly aligned with threaded end 21.

The end of adaptor 24 remote from threaded socket 26 is provided with a socket 28 formed by slotting the adaptor 24 along its longitudinal axis. The socket 28 has an enlarged arcuate portion 30 intermediate its lip portion 32 and its base portion 34.

The socket 28 is formed so as to receive the bulbous head 36 of the crown-stem of watch crown 38. Bulbous head 36 is thrust between the lips 32 of socket 28 with the head portion aligned so that its arcuate sides, which mate with the arcuate sides of arcuate portion 30, are received within the arcuate portion 30 of socket 28.

Adaptor 24 is mounted on stem 10 by first cutting off the excess portion of threaded end 21 of stem 10, as for example, along the dotted line shown in Figure 1. This may be accomplished by the watch repairman at his bench, and the requisite amount of threaded end 21 which must be cut away in any given instance will depend upon the model and type of watch to which the stem is being applied. After the excess portion of threaded end 21 has been cut off, the adaptor 24 is threadably joined to stem 10 by threadably engaging the end 21 in the threaded socket 26 to produce the winding stem 10a of the present invention shown in Figure 3.

Figure 4 shows the winding stem 10a of the present invention operatively positioned in a watch of the present invention. Thus, the watch stem 10a of the present invention is shown within a watch-case having a solid back 40 integrally joined with its rim 42. The winding stem 10a projects through the tube or sleeve 44 whose outer end is engaged with a gasket 46 carried by crown 38, whereby the watch is rendered waterproof. As will be seen from Figure 4 the bulbous head 36 of the crown-stem of crown 38 is frictionally axially engaged within socket 28 of adaptor 24, which is engaged with the remainder of the stem 10a by threaded engagement between threaded end 21 and threaded socket 26. The winding stem 10a projects as an axial extension of the crown 38 permitting its rotation upon rotation of the crown.

The present invention may be embodied in other specific forms without departing from the spirit or essential attributes thereof and, accordingly, reference should be made to the appended claims, rather than to the foregoing specification as indicating the scope of the invention.

I claim:

- 60 1. In a timepiece a watch-case formed with a solid back and an integral rim, a two-piece winding stem rotatably mounted on said watch-case, said winding stem including a cylindrical portion having an axially extending slotted socket at its outer end and an axially extending threaded socket at its inner end, an elongated stem element screw-threadedly secured to said threaded socket and projecting within said watch-case, and a crown comprising an integral bulbous headed crown-stem, said bulbous headed crown-stem being frictionally axially engaged with said axially extending slotted socket.
- 65 2. In a timepiece a watch-case formed with a solid back

and an integral rim, a two-piece winding stem rotatably mounted on said watch-case, said winding stem including a cylindrical portion having an axially extending slotted socket at its outer end and an axially extending threaded socket at its inner end, a crown comprising an integral bulbous headed crown-stem, said bulbous headed crown-stem being frictionally axially engaged with said axially extending slotted socket, an elongated stem element screw-threadedly secured to said threaded socket and projecting within said watch-case, said stem element including a pilot bearing at the end thereof remote from said cylindrical portion, a winding pinion square adjacent said pilot bearing, and a detent slot intermediate said cylindrical portion and said pilot bearing.

3. In a winding-up-device for watches, a winding stem including a cylindrical portion having an axially extending slotted socket at one end and an axially extending threaded socket at the other end, an elongated stem element having a threaded end threadably secured with said threaded socket, said elongated stem portion including a pilot bearing at its end remote from its threaded end, a winding pinion square adjacent said pilot bearing, and a detent slot intermediate said threaded end and said winding pinion square. 15

4. In a timepiece a watch-case formed with a solid back and an integral rim, a two-piece winding stem rotatably mounted on said watch-case, said winding stem including a cylindrical portion having an axially extending slotted socket at its outer end and an axially extending threaded socket at its inner end, an elongated stem element screw-threadedly secured to said threaded socket and projecting within said watch-case, a unitary crown comprising an integral bulbous headed crown-stem, said bulbous headed crown-stem being frictionally axially engaged within said axially extending slotted socket, a sleeve 25

said crown-stem and a portion of said winding stem, an annular groove in said crown juxtaposed to the outer end of said sleeve, and a gasket within said groove adjacent the outer end of said sleeve.

5. In a timepiece a watch-case formed with a solid back and an integral rim, a two-piece winding stem rotatably mounted on said watch-case, said winding stem including a cylindrical portion having an axially extending slotted socket at its outer end and an axially extending threaded socket at its inner end, an elongated stem element screw-threadedly secured to said threaded socket and projecting within said watch-case, said stem element including a pilot bearing at the end thereof remote from said cylindrical portion, a winding pinion square adjacent said pilot bearing, a detent slot intermediate said cylindrical portion and said pilot bearing, a unitary crown comprising an integral bulbous headed crown-stem, said bulbous headed crown-stem being frictionally axially engaged within said axially extending slotted socket, a sleeve 10

projecting from the rim of said watch and embracing said crown-stem and a portion of said winding stem, an annular groove in said crown juxtaposed to the outer end of said sleeve, and a gasket within said groove adjacent the outer end of said sleeve. 20
